UNITED STATES PATENT OFFICE.

EDWIN FIRTH AND JACOB CORNTHWAITE, OF TROY, NEW YORK.

MACHINE FOR MAKING HORSESHOES.

SPECIFICATION forming part of Letters Patent No. 392,322, dated November 6, 1888.

Application filed April 25, 1888. Serial No. 271,762. (No model.)

To all whom it may concern:

Be it known that we, EDWIN FIRTH and JACOB CORNTHWAITE, citizens of the United States, residing at Troy, in the county of Rensselaer and State of New York, have invented a new and useful Improvement in Machines for Making Horseshoes, of which the following is a specification.

Our invention relates to an improvement in machines for making horseshoes; and it consists in the peculiar construction and combination of devices, that will be more fully set forth hereinafter, and particularly pointed out in the claims.

The object of our invention is to provide a machine which is adapted to make a number of horseshoes at a single operation and to entirely perfect the horseshoes and swage and punch the nail-holes in the same, so that the shoe will be absolutely completed when it leaves the machine.

In the accompanying drawings, Figure 1 is a top plan view of a horseshoe-machine embodying our improvement. Fig. 2 is a side elevation of the same. Fig. 3 is a transverse section on line *xx* of Fig. 2. Fig. 4 is a vertical longitudinal sectional view of the same. Fig. 5 is a detail perspective view of one of the hammers or plungers, showing the nail-hole punches secured thereto. Fig. 6 is a detail sectional view of the same, taken on the line *aa* of Fig. 5. Fig. 7 is a detail view, partly in section, of a portion of the driving-gear of the horseshoe-machine. Fig. 8 is a detail perspective view of the feed-box. Fig. 9 is an enlarged vertical transverse sectional view of the same. Fig. 10 is a detail top plan view of the die-plate and former, showing the same arranged in their proper relative positions. Fig. 11 is a detail top plan view of the die-plate. Fig. 12 is a detail perspective view of the former.

A represents the base or bed plate, which is quadrangular in shape, and is provided at a suitable distance from its rear end with a transverse opening, *B*.

C represents a transverse dovetailed tongue or spline, which is arranged on the upper side of the bed-plate, at a suitable distance from the rear end thereof, and is firmly secured to the bed-plate, either by bolting it thereto or in any other suitable manner.

D represents a series of vertical standards, which have the widened treads or feet at their bases, are widened or swelled at a suitable distance from their lower ends on opposite sides, to form transverse enlargements *F*, are similarly swelled on opposite sides at a suitable distance above the enlargements *F*, to form transverse horizontal enlargements *G*, and have bearings *H* formed at their upper ends. The lower ends of the said standards are provided with transverse dovetailed recesses *I*, to receive the dovetailed tongue or spline *C*, and a gib, *K*, is placed between the rear side of the said spline or tongue and the opposing sides of the recesses *I*, as shown. The said standards are arranged at suitable regular distances apart, and are each provided with a clamping-screw, *L*, which bears against the rear side of the gib and serves to secure the standards firmly in position.

M represents a shaft or rod, which extends transversely through the standards *D* at a suitable distance below the enlargements *F*. Said shaft or rod is fixed in the standard, and is not adapted to rotate, and serves the purpose of bracing the standards and preventing lateral vibration thereof. The ends of the said rod or shaft project beyond opposite sides of the machine, and on one end of the said shaft is fitted a loose driving-pulley, *N*, and on the opposite end thereof is fitted a loose double pulley, *O*. On the inner end or side of the loose driving-pulley *N* is a peripherally-grooved collar, *P*, and one member, *R*, of a clutch.

S represents a miter gear-wheel, which is also loose on the shaft or rod *M*, and is provided on its outer side with a clutch member, *T*, which is adapted to be engaged by the clutch member *R*, so as to enable the rotary motion of the driving-pulley *N* to be communicated to the miter-wheel *S*.

U represents a pair of arms or brackets which project from one side of the bed-plate, and *V* represents a rock-shaft which is journaled in said arms or brackets. The said rock-shaft is provided with an arm, *W*, that engages the grooved collar *P*, and has a lever, *X*, by means of which the rock-shaft may be operated so as to throw the pulley *N* into or out of engagement with the miter-wheel *S*.

Y represents a series of shafts, which are

journaled in the bearings H at the upper ends of standards D. To the rear end of each of the said shafts is keyed a worm-wheel, Z. To the front end of each of the shafts Y which are 5 on the sides of the machine is secured an eccentric, A', and to the front end of each intermediate shaft, Y, is secured an eccentric, B'.

C' represents a pair of pitmen, which are provided at their upper ends with eccentric straps D', that engage the eccentrics A'. Said pitmen depend from the said eccentrics, and are provided at their lower ends with bearings E', in which is journaled a saw-arbor, F'. The said bearings are connected to the standards 10 D at the sides of the machine by means of links G', the function of the said links being to prevent the bearing and the shaft or saw-arbor from swinging either laterally or longitudinally, while allowing said arbor and bearings to move in a vertical direction. On one 15 end of the shaft or arbor is secured a pulley, H', which is connected to the pulley O by means of an endless belt, I'.

K' represents a series of circular saws, which 20 are secured to the shaft or arbor F' at suitable regular distances apart by means of collars L', which are clamped to the arbor on opposite sides of the saws by set-screws M'. The said saws are arranged midway between the standards 25 D, as shown in Figs. 1 and 3.

N' represents a series of die-plates, which are of the shape shown in Fig. 11, and are each provided with a rearwardly-extending spindle or arm, O'. Each die-plate is provided 30 with a central opening, P', which conforms to the shape of the horseshoe, and has its front side provided with an opening, R'. On the upper side of each die-plate, on opposite sides of the same, are parallel flanges S'.

T' represents a series of formers, each of which is of the exact size and shape of the horseshoes to be made by the machine, and said formers are provided on their under sides with the depending core U', the shape of which 35 corresponds with the inner side of the horseshoe, a recess or mold, V', being thereby formed in the edge of each former. From the front end of each former, at the upper side thereof, projects a lip or flange, W', and from the rear end of each former projects an arm, X'. Each former is arranged on the upper side of its companion die-plate, and the opposing sides of the arms X' and O' are flattened, so that said 40 arms bear snugly against each other, and the said arms are inserted in countersunk openings Y', which are made transversely in the enlarged portions F of standards D, as shown in Fig. 4. The inner sides of the formers and die-plates enter recesses in the front sides of 45 the standards D, and thereby the die-plates and formers are maintained in perfectly horizontal planes. The upper side of each die-plate is at a suitable distance below the under side of its companion former, and thereby a horizontal opening, Z', is formed between each die-plate and its companion former, as 50 shown in Fig. 4.

On the upper side of the bed-plate A, near the front end thereof, is a transverse dovetail tongue or spline, A².

B² represents a pair of standards, which are provided at their lower end with dovetailed recesses to receive the tongue or spline A². Gibs C² are placed between the front side of the spline or tongue and the opposing side of 75 the dovetailed recess in each standard, and clamping-screws D² are provided for the said standards, which bear against the gib, and thereby firmly secure the standards in place.

E² represents a shaft, which is journaled in 80 suitable bearings in the standards B². To one end of the said shaft is keyed a worm-wheel, F², and a suitable number of eccentrics, G², are also secured to the said shaft and arranged at suitable regular distances apart.

H² represents a dovetailed tongue or spline, which is arranged transversely on the upper side of the base-plate at a suitable distance from the front end thereof.

I² represents a series of guide standards, 90 which have dovetailed recesses in their lower ends to receive the said tongue or spline, and said standards are secured in position at suitable regular distances apart by means of gib K² and clamping-screws L², as shown in Figs. 95 2 and 4.

M² represents a series of longitudinal rods, which are guided in bearings in the upper ends of the standards I² and are adapted to reciprocate therein. To the front end of each 100 rod M² is pivotally connected a pitman, N², and the said pitmen are provided at their front ends with eccentric-straps O², which connect them to the eccentrics G². The rear end of each rod M² is provided with a broadened 105 head, I², and in each of the said heads are pivoted the front ends of a pair of arms, R². The said arms are adapted to move laterally in horizontal plane, and are provided each at its rear end with a vertical pin, S².

On the upper side of each die plate N' is arranged a plate, T², the said plates T² being adapted to be guided in a longitudinal direction on the die-plates by the flanges S' of the latter. The upper side of each plate T² is inclined longitudinally, as shown in Figs. 2 and 4, and each plate T² is provided at a suitable distance from its inner or rear end with a transverse slot, U². The pins S² of the arms R² enter the said slots and are normally in the 110 openings R' of the die-plates, so that the pairs of arms R² are arranged side by side and in contact each with its fellow. Each former is provided with a number of vertical openings, c, which correspond with the nail-holes in a 115 horseshoe, and each plate T² is provided with similar openings, d, which are adapted to register with the openings c when the plates are moved inward under the formers, as will be hereinafter described.

V² represents a series of brackets, which project from the front sides of the standards D, and have the rearwardly-extending arms, which are secured in openings in the enlarged por-

tions G of said standards by means of set-screws W², as shown in Fig. 4.

X² represents a series of plunger-rods, which are guided in vertical openings in the brackets V², and have their upper ends provided with eccentric-straps Y², which engage the eccentrics B'. In the lower end of each plunger-rod X² is made a vertical recess or socket.

Z² represents a series of hammers or plun-
gers, the construction of each of which is as follows:

A³ represents a plate of suitable size, which is substantially in the form of a horseshoe and is provided at a suitable distance from its front and rear end with transverse slots B³. From the upper side of the plates near the center of the same, projects a spindle or arm, C³, which is adapted to enter the recess or socket in the lower end of one of the plunger-rods X², and is secured therein by means of a set-screw, D³.

E³ represents a pair of plates, which are arranged on the lower side of the plate A³, and are secured thereto by means of bolts F³, which pass downward through the slots B³ and enter the said plates. The outer sides of the plates E³ conform to the contour of the plate A³, and in the opposing edges of the said plates E³ is made a tapered threaded opening, G³.

H³ represents a tapered screw-plug, which engages the said opening. By loosening the bolts F³ and turning the tapered screw-plug the plates E³ may be moved laterally toward or from each other, so as to adjust the hammer or plunger to any desired width, as will be readily understood. The plates E³ are provided with vertical openings, which are similar to the openings c and d of the formers and plates T², respectively, and in the said openings in plates E³ are inserted the upper ends of vertical depending punches I³, which are adapted to punch the nail-holes in the horseshoes, as will be hereinafter described, and are secured to the plates E³ by means of set-screws K³.

L³ represents a feed-box, which is arranged transversely over the saws and over the outer ends of the die-plates and has its inner side open, as shown in Figs. 4, 8, and 9. In the upper side of the feed-box, at suitable regular distances apart, are vertical transverse slots M³.

N³ represents a feed-bar, which is arranged in the feed-box, extends entirely throughout the length thereof, and has one end enlarged, as at O³. On the under side of the feed-bar is a longitudinal groove, P³, and from the outer side of the feed-bar depends a vertical flange, R³.

S³ represents a series of stop-pins, which project from the upper side of the feed-bar N³ and work in the slots M³, the function of the said pins and of the slots being to limit the lateral play of the feed-bar in the feed-box. From the inner side of the feed-bar, near the upper edge thereof, project a series of screw-eyes or keepers, T³, and in the rear side of the feed-bar and at a suitable distance from its upper

side is a horizontal longitudinal open slot, U³. The projecting lips W³ of the formers enter said open slot U³, and thereby secure the feed-bar on the formers and over the outer end of the die-plates and over the saws.

V³ represents rods, which project forward from the standards D, at suitable distances apart, and have eyes formed in their outer ends and arranged on the sides of the screw-eyes T³. A rod, W³, passes through the eyes in the rods G³ and through the screw-eyes T³, and thereby serves to connect the feed-bar to the rods V³, the function of the latter being to secure the feed-bar against movement.

X³ represents arms or brackets, which project rearward from the end standards, D, near their upper ends. In the rear ends of the said arms or brackets is journaled a shaft, Y³, which is provided with worm-wheels Z³, that engage the worm-wheels Z.

A⁴ represents a miter gear-wheel, which is secured to one end of the shaft Y³.

B⁴ represents a horizontal arm or bracket, which is secured on the outer side of one of the end standards D. In the said arm or bracket is journaled a vertical shaft, C⁴, which is provided at its upper end with a miter-wheel, D⁴, that meshes with the wheel A⁴. To the lower end of the said shaft is secured a miter-wheel, E⁴, that meshes with the wheel S.

From the foregoing description it will be understood that when the pulley N is rotated and is geared to the wheel S rotary motion is transmitted to the shaft C⁴ by the wheel E⁴, from the shaft C⁴ to the shaft Y³ by the miter-gears A⁴ and D⁴, and from the shaft Y³ to the shafts Y by the worm-gears Z³ and Z.

F⁴ represents a pair of bearings which project from one side of the base-plate, and in the said bearings is journaled an incline-shaft, G⁴, which is provided at one end with a worm, H⁴, that meshes with the worm-wheel F², and is provided at its opposite end with a miter-wheel, I⁴, that meshes with the wheel S.

From the foregoing description it will be understood that the rotary motion of the wheel F, when the driving-pulley N is clutched thereto, will be transmitted to the shaft G⁴ through the miter-wheel I⁴, and from the said shaft to the shaft E² by the worm H⁴ and worm-wheel F². The pulley O is connected to a driving-pulley on a suitable counter-shaft (not shown) by means of a suitable endless belt, K⁴, which is illustrated by dotted lines in Fig. 1.

The operation of our invention is as follows: When the horseshoe-machine is in its initial position, the plates T² are drawn outward from between the die plates and formers, the saw-arbor is lowered, the plungers or hammers are raised, and the arms R² are in contact with each other in pairs, and the pins S² are in the openings R' of the die-plates. A bloom is heated in a suitable furnace, is passed through the passes of a set of rolls of the usual construction in a suitable manner, the said rolls being adapted to convert the bloom into a rod or blank, e, which is of suitable length

to make a number of horseshoes, according to the capacity of the machine, and the said rolls make the creases which are to appear in the horseshoes in the said blank-rod, as is now customarily done. The said blank-rod, while still heated and ductile, is fed from the last pass of the rolls directly into the groove P^3 of the feed-bar N^3 , said blank-rod being supported upon the bottom ledge or flange of the feed-box L^3 , as shown in Fig. 9. The operator then grasps the feed-box and moves the same outward from the standards D , thereby causing said feed-box to move from the feed-bar, so that the lower flange or ledge of the feed-box passes from under the blank-rod e , and thereby causes said blank-rod to drop upon the inner end of the plates T^2 and to bear against the inner sides of the pins S^2 . The mechanism of the horseshoe-machine is so timed that as soon as the blank-rod is dropped upon the said plates T^2 the eccentrics D and A' pass their lower dead-centers and consequently draw the plunger-rods X^2 and the pitmen C' upward, thereby elevating the plungers and the punches attached thereto, and also elevating the saw-arbor and the saws, so as to cause the upper edges of the latter to rise between the die-plates, and consequently cut the blank-rod into pieces of suitable length to be bent into horseshoes. The saws and the plungers or hammers then begin to descend, being caused to do so by the eccentrics A' B' , as will be readily understood, and the eccentrics G^2 and pitmen N^2 then cause the rods M^2 to move forward, and consequently impart forward longitudinal movement to the hinged or pivoted arms R^2 , thereby causing the pins S^2 of the latter to engage the rear sides of the horseshoe-blanks and move the latter and the plates T^2 forward. As the said blanks and said plates move forward, the central portions of the blanks first strike against the front ends of the depending cores U' of the formers, which cores arrest the forward motion of the central portions of the blanks. The pins S^2 impinge against the curved sides of the formers as the arms R^2 continue to move rearward, thereby causing the said pins to be guided in the cam-slots, which are formed between the outer sides of the formers and the inner sides of the openings P' of the die-plates, the result being that the said pins bend the still heated blanks around the cores of the formers, thereby causing the said blanks to fill the molds of the formers and to bear between the lower sides of said formers and the upper sides of the plates T^2 . Owing to the slots U^2 , with which said plates T^2 are provided, the pins S^2 are caused to recede from and approach each other as they travel around the curved sides of the formers, and said plates are caused to move inward under the formers and to keep pace with the said pins, so that the blanks are at all times maintained upon the said plates while being bent around the cores of the formers.

Owing to the inclination of the upper sides

of the plates T^2 , the molds in the formers are deeper at the points thereof corresponding to the heels of the shoes than they are at their outer sides, and the shapes of the molds are such that the heels of the blanks are contracted in width, thereby as the pins S^2 travel around the sides of the formers, when they approach the rear ends thereof, the inner sides of the openings P' of the die-plates cause the pins S^2 to swage the ends of the blanks in the molds and thereby give the horseshoes the necessary swell-heels and complete the operation of forming the horseshoes, so that no subsequent forging or manipulation of the horseshoes will be necessary. By the time that the pins S^2 reach the rear ends of the cam-slots between the die-plates and the formers, and before the rods M^2 and arms R^2 start in their reversed longitudinal movement, the plungers or hammers have been lowered by the plunger-rods and their operating eccentrics or cams B' , so that the punches have descended through the now aligned openings c d of the formers and plates T^2 and are being forced downward through the horseshoe-blanks, so as to punch the necessary nail-holes therein. While the plungers are at the lower end of their movement and the punches have trans-fixed the horseshoes, said plungers and punches serve to hold the horseshoes rigidly in place in the molds of the formers. As the arms R^2 recede, the pins S^2 are caused to pass backward around the sides of the formers and to impinge so firmly against the sides of the horseshoe-blanks that the swells or enlargements made in the outer edges of the same by the act of forcing the punches through the horseshoes are rolled out, thereby restoring the outer edges of the horseshoe-blank to the requisite configuration and imparting finished surfaces thereto. It will be understood that as the pins S^2 recede they draw the plates T^2 outward with them, and as the horseshoe-blanks are still held in the molds of the formers by the punches, as before stated, the said plates T^2 move from under the said horseshoe-blanks so as to uncover the openings P' in the die-plates. By the time that the plates T^2 are withdrawn entirely from under the formers and the horseshoes a second blank-rod is fed into the feed-rod, the saws rise and cut the same into lengths, as before described, and the plungers or hammers rise simultaneously with the saws, withdraw the punches from the completed horseshoes, and the latter then drop in a finished condition through the openings P' of the die-plates and through the openings B of the base or bed plate onto the floor or into a suitable receptacle.

Having thus described our invention, we claim—

1. The combination of the rigid die-plate having the opening P' and the opening R' , communicating therewith, the rigid former arranged in proximity to the die-plate, and the arms R^2 , having the pins S^2 , adapted to traverse the openings formed between the sides of

the former and the sides of the opening in the die-plate, and means, substantially as set forth, to operate the arms R^2 , substantially as described.

5 2. The combination of the rigid die-plate having the opening P' and the opening R' , communicating therewith, the former arranged over the die-plate and concentric with the opening P' , the arms R^2 , movable longitudinally and laterally and having the pins S^2 , and the plate T^2 , adapted to slide on the die-plate and having the transverse slot U^2 , with which the pins S^2 engage, substantially as described.

15 3. The combination of the die-plate having the opening P' and the communicating opening R' , the former arranged over the die-plate and concentric with the opening P' , the slide-plate T^2 , arranged on the die-plate and having the transverse slot U^2 , said plate T^2 and the former being provided with openings d and c , respectively, adapted to register when the plate T^2 is over the die-plate, and the longitudinally and laterally movable arms R^2 , having the pins S^2 engaging the slot U^2 and adapted to operate between the die-plate and the former, substantially as described.

30 4. The combination of the die-plate having the opening P' , communicating opening R' , and the flanges S' , the former arranged over the die-plate and concentric with the opening P' , the arms having the pins S^2 , for the purpose set forth, and the plate T^2 , guided on the die-plate by the flanges S' , and having the transverse slot, into which the pins S^2 extend, substantially as described.

35 5. The former having the core U' on one side, thereby forming the mold V' , substantially as described.

40 6. The combination, in a machine for making horseshoes, of the die-plate having the opening P' and the communicating opening R' , the former arranged over the die-plate and concentric with the opening P' , the slide-plate T^2 , arranged on the die-plate and having the transverse slot U^2 , the operating-arms R^2 , having the pins S^2 working in the slot and in the cam-openings between the former and die-plates, said slide-plate and former having the openings adapted to register when the slide-plate is entirely under the former, and the plunger or hammer having the punches adapted to be forced through the registering openings in the slide-plate and former and through a blank in the mold of the former, substantially as described.

45 7. The combination, in a machine for making horseshoes, of the series of die-plates and formers, the operating-arms having the pins to pass between the concentric sides of the die-plates and formers, for the purpose set forth, means, substantially as set forth, to guide a blank-rod, and the saws or cutters to cut the blank-rods into sections of suitable length, substantially as described.

50 65 8. The combination, in a machine for making horseshoes, of the rigid die-plate having the opening P' and communicating opening

R' , the rigid former arranged over the die-plate and concentric with the opening P' , the arms having the pins S^2 , the slide-plate T^2 , arranged on the die-plate and having the transverse slots through which the pins extend, said slide-plate and former having the openings adapted to register, the vertically-movable plunger having the punches, and mechanism, substantially as specified, to operate the arms and the plunger, substantially as described.

70 9. The combination, in a machine for making horseshoes, of the die-plate having the opening P' and communicating opening R' , the former arranged over the die-plate and concentric with the opening P' , the slide-plate arranged on the die-plate and having the slot U^2 , the shaft having the eccentric G^2 , the reciprocating rod M^2 , supported in a suitable guide and connected to the eccentric and actuated thereby, and the arms R^2 , hinged or pivoted to the reciprocating rod, and having the pins S^2 engaging slot U^2 and adapted to travel in the slots between the opening in the die-plate and the sides of the former, substantially as described.

80 10. The combination, in a machine for making horseshoes, of the die-plates and formers, the eccentrics A' , the pitmen engaging said eccentrics and depending therefrom, the saw shaft or arbor journaled in said pitmen, the saws attached to said shaft and arranged between the die-plates, and means, substantially as set forth, to rotate the said shaft, substantially as described.

85 11. The combination, in a machine for making horseshoes, of the die-plates and formers, the slide-plates T^2 , arranged on the die-plates, the feed-bar adapted to feed the blank-rods to the slide-plates, and the vertically-movable revoluble shaft or arbor having the circular saws or cutters to sever the blank-rods in sections, substantially as described.

90 110 12. The combination, in a machine for making horseshoes, of the standards D , the die-plates and formers secured thereto, the shafts Y , journaled on the standards and having the eccentrics B' , the plungers having the punches, connections between said plungers and the eccentrics B' , the slide-plates T^2 , arranged on the die-plates, the arms having the pins movable between the die-plates and formers and engaging slide-plates and movable laterally therein, the reciprocating rods connected to said arms, the shaft E^2 , having the eccentrics, the pitmen connecting said eccentrics to the rods M^2 , the driving-wheel N , and gears, substantially as specified, to communicate motion from said driving-wheel to the shafts Y and E^2 , substantially as described.

the purpose set forth, the shaft E², journaled in suitable bearings and having the eccentrics G² and worm-wheel F², the pitmen connecting eccentrics G² with the rods M², the shaft Y³, 5 geared to the shafts Y, the shaft C¹, geared to the shaft Y³, the driving wheel or pulley geared to the shaft C¹, the shaft G¹, having the worm-engaging wheel F¹, and the gear connecting said shaft to the driving wheel or pulley, substantially as described.

14. In a plunger for punching holes in blanks, the combination of the plate A³, having slots B³, the plates E³, adapted for the attachment of the punches, and the bolts working in slots 15 B³ and engaging the plates E³, substantially as described.

15. The combination of the plate A³, the plate C³, secured thereto and movable laterally thereon, and the punches secured to said plates, 20 substantially as described.

16. The combination of the plate A³, the plates E³, secured thereto and movable laterally thereon, said plates being adapted to secure the punches and having the tapered 25 threaded opening in their meeting edges, and the tapered screw-plug engaging said threaded opening, substantially as described.

17. The combination of the die-plates and formers, the feed-box having the longitudinal 30 opening in one side, and the feed-bar movable laterally in the feed-box and having the longitudinal groove I³ in its lower side, substantially as described.

18. The combination of the feed-box, open on 35 one side and having the transverse slots M³, the feed-bar movable laterally in the feed-box and having the groove I³ in its lower side, and the pins S³, projecting from the feed-bar and working in the slots M³, substantially as described.

19. In a horseshoe-making machine, the combination of the rigid die-plate having the opening P', which conforms to the shape of the horseshoe, the former T', of the shape and size 45 of the horseshoe, arranged over the die-plate concentric with the opening P', and the arms R², having pins adapted to bend the horseshoe-blank around the former.

20. In a horseshoe-machine, the former T', 50 having the shape and size of the horseshoe, and provided with the depending core U', combined with the arm R², having the pins S² to bend the horseshoe-blank around the core of the former, as set forth.

21. In a horseshoe-machine, the rigid die-plate having the opening P', the former T', arranged over the die-plate and concentric with the opening P', the plate T², adapted to slide, and the arms R², having the pins S², for the 60 purpose set forth.

22. In a horseshoe-machine, the former T', having the shape and size of a horseshoe and provided with the depending cover U', the die-plate having the opening P, and the mechanism, substantially as described, to bend the 65

horseshoe-blanks around the core of the former, as set forth.

23. In a horseshoe-machine, the die-plate, in combination with the former, and the operating-arms having the pins to pass between 70 the concentric sides of the die-plate and former, as set forth.

24. In a horseshoe-machine, the die-plate and former, the operating-arm having the pins to pass between the concentric sides of the die-plate and former, for the purpose set forth, and the plunger or hammer having the punches adapted to be forced through openings of the former, as set forth. 75

25. The former of a horseshoe-machine, having the core U' on one side thereof forming the mold V', and the openings c in the mold, as set forth.

26. In a horseshoe-machine, the feed-box, open on one side, combined with the feed-bar 80 movable laterally in the feed-box, as set forth.

27. In a machine for making horseshoes, the die-plates and formers, the slide T², the feed device adapted to feed the blank-rods to the slide-plates, the vertically-movable revolute shaft or arbor having the saws or cutters arranged between the die-plates and the punches and plungers, the mechanism being so timed that as soon as the blank-rod is dropped upon the slide T² the plunger and punches 95 and the saw-arbor are drawn up so as to cause the upper edge of the saws or cutters to rise between the die-plates, and consequently cut the blank-rod in sections, as set forth.

28. In a horseshoe-machine, the combination, 100 with the feeding mechanism for the blank-rods, of the vertically-movable revolute saw-arbor having the saws or cutters, as set forth.

29. In a horseshoe-machine, the vertically-movable plungers carrying the punches, the 105 die-plate, the formers having the openings C, and the slide-plates T², having openings registering with the openings of the formers, as set forth.

30. In a horseshoe-machine, the die-plate 110 and formers, the latter having the openings C, combined with the punches, the feeding mechanism, and the slide-plates receiving the blank-rods from the feeding mechanism, and having openings d registering with the openings C, 115 the said punches passing through the openings e d, respectively, as set forth.

31. In a horseshoe-machine, the combination of the die-plates and formers, the vertically-movable revolute saws or cutters, and the 120 feeding mechanism for feeding the blank-rods, as set forth.

In testimony that we claim the foregoing as our own we have hereto affixed our signatures in presence of two witnesses.

EDWIN FIRTH.

JACOB CORNTHWAITE.
